DISPOSABLE SURGICAL MASK

Hillary G. Waits, Jr., 4002 W. 18th St., Wichita, Kans.

Filed Sept. 18, 1961, Ser. No. 138,767

5 Claims. (Cl. 128—146)

This invention relates to protection against contamination. More specifically, this invention relates to protection of people against contaminants present in the air, such as bacteria and the like. Still more specifically, this invention relates to an improved surgical mask, for use in two way protection of patients and doctors, nurses, dentists and the like. Yet more specifically this invention relates to a disposable surgical mask having an improved air filtration and cleaning means, for use by doctors and nurses in operating rooms, other hospital rooms, and the like, where close contact between personnel and patient are necessary.

Various types and designs of surgical masks are known to the prior art. The principal disadvantage of these masks is that they do not perform effectively the function of cleaning the exhaled and inhaled air, this having been shown by clinical tests. Attempts to increase the effectiveness of the masks have not been particularly successful and they have caused additional problems. For example, the problem of contamination was attempted to be solved by increasing the amount of filtering material included in the mask. This, however, caused increased air flow around the sides of the mask, which air is not filtered at all. This was attempted to be solved by various means of holding the mask tight against the surface of the face. This resulted in shortness of breath, impairment of circulation to the head, and other objectionable symptoms. The common and usual surgical mask of layers of cloth fabric in a very short time becomes moist and saturated with moisture losing its effectiveness entirely. From 30 to 45 minutes is considered a long life for the commonly used mask.

My invention solves these problems of the masks of the prior art by new structure of mask utilizing therein materials not commonly used for such purposes, namely preferably special cellulose materials, to filter the air, in place of the usual surgical gauze, firmly woven fabric or the like material adapted to have a filtering effect. One reason for the increased effectiveness of the preferred cellulose material is that it not only mechanically filters the air, but it also *absorbs* the water contained therein without losing effectiveness, and at the same time, of course, retains any suspended bacteria. Clinical tests comparing prior art masks and the masks of my invention have been made, such tests including bacteria counts, and my new mask has been found to be unexpectedly more effective.

More specifically the new surgical mask of my invention comprises a filtering and cleaning portion, preferably composed of loosely compacted cellulose material which is desirably reinforced with spaced threads, and shaped so as to encourage inhaled and exhaled air to pass generally along and longitudinally through the cellulose mass rather than directly or transversely through the mask, increasing the filtering, absorbing and cleaning action of the cellulose, this being done preferably by pleating. This cellulose material is preferably in the form of loosely piled layers of non-woven material. From 5 to 15 layers have been found desirable and effective. However, any suitable number of layers can be used. The high absorbency of the thread reinforced cellulose material increases the life of the mask. This portion is of such a size as to easily cover the nose and mouth of the wearer, with the pleating aiding in this. A sheet or layer which is impervious to air and moisture is also preferably provided on the outer side of the mask, and this tends to eliminate direct air flow

2

through the mask, and instead directs the air in and out the sides of the mask and through the cellulose in filtering relation, increasing the contact time between the air and the cellulose. Binding tapes or the like are provided to secure the mask to the head of the wearer. The mask is desirably worn with the impervious layer away from the face. Because of the improved structure and mask materials of the new surgical mask of my invention, it is not necessary for the mask to fit tightly, and a prime source of discomfort to a wearer is thus eliminated. Also, the soft, fluffy and flexible nature of the materials used in the mask adds to the mask's comfort and effectiveness. Not least among the advantages of my new surgical mask is that the materials of which it is made can all be obtained cheaply, thus encouraging the discarding of a mask after one use.

It is an object of this invention to provide a new contamination prevention means.

Another object of this invention is to provide a new means of protecting people against contamination present in the air such as bacteria.

It is still another object of this invention to provide an improved surgical mask, for use in two-way protection of patients and doctors, nurses, dentists and the like.

It is yet another object of this invention to provide a disposable surgical mask having an improved air filtration and cleaning means, for use by doctors and nurses in operating rooms, other hospital rooms, and the like where close contact between such personnel and patient is necessary.

It is yet another object of this invention to overcome the disadvantages and difficulties of the surgical masks of the prior art.

Other objects and advantages of the new mask of my invention will be obvious and will become apparent to those skilled in the art upon reading this disclosure.

Drawings accompany and are a part of this disclosure. These drawings depict preferred specific embodiments of the new surgical mask of my invention, and it is to be understood that such drawings are not to unduly limit the scope of my invention.

In the drawings,

FIG. 1 is a front view of one preferred specific embodiment of the new surgical mask structure of my invention, showing a mask with a vapor barrier stitched on all four sides, and a reinforced cellulose material layer on the back only.

FIG. 2 is a view of the back of the mask of FIG. 1, with the various layers of cellulose material comprising the mask body shown partially cut away.

FIG. 3 is a cross-sectional view taken along the line 3—3 in FIG. 1.

FIG. 4 is an isometric view of a person wearing this new surgical mask of my invention.

FIG. 5 is a front view of another preferred specific embodiment of the new surgical mask structure of my invention, showing a mask with a vapor barrier loose on two sides, and a reinforced cellulose material layer on both sides, and partially cut away to show the various layers of cellulose material comprising the mask body.

FIG. 6 is a back view of the mask of FIG. 5 and showing a metal nose piece in place for use.

FIG. 7 is a cross-sectional view through FIG. 5 along the line 7—7.

FIG. 8 is a section view through FIG. 6 along line 8—8, and showing the nose piece.

Following is a discussion and description of new surgical mask structures of my invention made with reference to the drawings wherein the same reference numerals are used to indicate the same or similar parts and/or structure. The discussion and description are of preferred specific embodiments of the new surgical mask structure of my invention, and it is to be understood

that such is not to unduly limit the scope of my invention.

Referring now to the drawings, FIGS. 1 through 4 are depictions of one of the preferred specific embodiments of my invention.

The cellulose mask pad or body portion 10 of the new mask of my invention preferably has a loosely piled plurality of non-woven absorbent cellulose material layers 11, 12, 14, 16 and 18. Any suitable number of layers can be used, depending upon the porosity and looseness of the sheet cellulose material employed, from 7 to 10 having been found satisfactory. They are preferably of relatively loosely composed cellulose material. The innermost cellulose layer 20 is preferably reinforced with threads in mesh configuration sewn therethrough and thereon. On the outer surface, and attached thereto in any suitable manner is a non-porous sheet 22 of impervious material preferably polyethylene film. Sheet 22 can be attached in any suitable manner such as by sewing or cementing it to the mask body 10. And, if desired barrier 22 can be provided by coating the outer cellulose layer with a suitable material to make it impervious, preferably centrally, for example by spraying with a plastic material, lacquer, etc. Over the top and bottom edges of the mask strips of cloth tapes 24 and 26 are preferably mounted. These bind the mask and the extensions thereof serve as ties to mount the mask (FIG. 4). The above-named parts are desirably held firmly in place by stitching 28 except for non-porous sheet 22 which can most conveniently be cemented in place. The various cellulose material layers of body 10 are preferably pleated at 30 and 32, and these pleats are maintained by the stitching at each end portion of the mask.

FIGS. 5 through 8 depict another preferred specific embodiment of the new surgical mask structure of my invention. In this embodiment, cellulose pad or mask body 40 has a number of loosely piled non-woven absorbent layers 41, 42 and 44. Here again any suitable number of layers can be employed to form body 40, from 7 to 10 being preferred. Preferably, on the front side of this pad 40 is a layer 46 of loose cellulose material reinforced with threads in mesh configuration therethrough and thereon. On the back side is a similar layer 48, preferably. Attached to the middle portion of the front side at its top and bottom ends only is a non-porous impervious sheet 50 preferably of polyethylene film or the like. Sheet 50 preferably has the same width as pad 40, but has a shorter length either than pad 40 or its own width. This serves to prevent flow of air directly outward from the mouth. The multiple cellulose material layer portions of mask body 40 are preferably bent to form two parallel pleats 52 and 54. Along the top and bottom sides of this mask run two fabric tapes 56 and 58, the extensions of which serve as mounting ties. The lengths of tapes 56 and 58 are preferably five times the length of pad 40. Holding the mask together on each of its four sides is stitching 60. Other suitable means such as a cement can be used, if desired. Nose piece 62 preferably made of a bendable metal strip and insertable at slit 64, is located between and held in place by the fabric tape and the cellulose material, and serves in use to shape the mask around the nose of the wearer, helping to prevent fogging of glasses from moist breath escaping upwardly.

The new mask structure of my invention is mounted and used as shown in FIG. 4 of the drawings, and it has been found that it can be comfortably worn for several hours straight without losing its protection effectiveness. Embodiments utilizing the cemented barrier 22 have proven particularly advantageous since such has no hindrance to air flow through the cellulose material. The mask reinforced layer of cellulose material resulting from the sewing has been found to work to prevent packing of the desirably loose layers of cellulose material and to prevent tearing, since it adds great strength to the mask structure.

In the following is set forth examples of the new mask of my invention. It is to be understood that the test conditions, materials, etc., set forth are not to unduly limit the scope of my invention.

Example

Various bacteriological studies were performed on the surgical mask of my invention as shown in FIGS. 1 to 8 of the drawings and described hereinbefore. Test series #1 hereinbelow was performed with the surgical mask having the polyethylene barrier layer open at two sides and adjacent to a layer of reinforced cellulose. Test #2 was performed with the surgical mask having the polyethylene layer which has cemented edges and which is adjacent to a layer of non-reinforced cellulose. The tests were performed as follows: Open auger plates were held approximately one inch from the mask, which was worn by the human test subject. Unless designated otherwise, at the time of the test, breathing was laborious to simulate operating conditions. The mask was worn throughout the test.

TEST #1

	Time Interval, Hours From Beginning	Area of Mask Tested	Results
25	0.5	Center	No growth obtained.
	1.0	do	One colony.
	1.5	do	No growth obtained.
	1.5	"R" side	Do.
	1.5	"L" side	Do.
	1.5 ^a	Center	Do.
	1.5 ^a	"R" side	Do.
	1.5 ^a	"L" side	One colony.
	1.5 ^b	Center	No growth obtained.
	1.5 ^b	"R" side	Do.
	1.5 ^b	"L" side	Do.

TEST #2

40	0.5	Center	No growth obtained.
	1.0	do	One colony.
	1.5	do	No growth obtained.
	1.5	"R" side	One colony.
	1.5	"L" side	No growth obtained.
	1.5 ^a	Center	One colony.
	1.5 ^a	"R" side	Do.
	1.5 ^a	"L" side	Do.
	1.5 ^a	Center	No growth obtained.
	1.5 ^a	"R" side	Do.
	1.5 ^a	"L" side	Do.
	1.5 ^b	Center	One colony.
	1.5 ^b	"R" side	No growth obtained.
	1.5 ^b	"L" side	Do.
	3.0	Center	Do.
	3.0	"R" side	Do.
	3.0	"L" side	One colony.
	3.0 ^a	Center	No growth obtained.
	3.0 ^a	"R" side	Do.
	3.0 ^a	"L" side	Do.
	3.0 ^b	Center	One colony.
	3.0 ^b	"R" side	Do.
	3.0 ^b	"L" side	Do.

^a With cough.

^b With sneeze.

Central tests made with the common and usual surgical gauze masks resulted in more than 500 growths.

As will be obvious to those skilled in the art, various changes and modifications of the preferred surgical mask structures disclosed herein can be made or followed without departing from the spirit of the disclosure or from the scope of the claims.

I claim:

1. A disposable surgical mask comprising, a rectangular porous absorbent pad of size to cover the nose and mouth of a human being, said pad being made of from 7 to 10 loosely piled layers of non-woven absorbent cellulose material, two cellulose material layers congruent with and stitched on four edges to said pad, one on each side of said pad and reinforced with threads in mesh configuration, said pad and said layers having two spaced and parallel pleats therein which divide said pad into three substantially equal portions each parallel to the long side of said rectangular pad, a non-porous and impervious polyethylene film on the outside of said mask having the same width as said pad but having a shorter length either than said pad or its own width,

centrally positioned so as to cover all except the two end portions of said pad and stitched on its two short or length sides to the middle portions of the long or length sides of said pad, two flexible binding tapes folded lengthwise over the long sides of said pad and stitched thereto, each of said tapes being approximately five times the length of said pad, and a flexible metal nose piece, inserted through a slit in the top one of said tapes on the back side, and held and located between said tape and said pad, said mask being used by tying each of said tapes around the head of the wearer, such that said non-porous layer is on the side away from the face, said porous pad and cellulose layers absorbing water and contaminants from the air as it passes along said pad and layers, said non-porous sheet serving to cause said passing air to travel further through said porous material, said nose piece being bent in the shape of the contour of the nose of the wearer and serving to prevent air from escaping upward and fogging the wearer's glasses, and said mask being disposable after use.

2. A disposable surgical mask comprising, an elongated rectangular flexible porous absorbent pad of size to cover the nose and mouth of a human being, said pad being made of from 7 to 10 loosely piled layers of non-woven absorbent material cellulose product, an inside cellulose material layer congruent with and stitched on four edges to said pad and reinforced with threads in mesh configuration, a non-porous and impervious polyethylene film on the outside of said mask having the same width as said pad but having a shorter length either than said pad or its own width, positioned so as to cover all except the two end portions of said pad, stitched on four sides to said pad, said layers having two large spaced and parallel pleats therein which form the central portion into a channel parallel to the long sides of said elongated pad, and two flexible binding tapes folded lengthwise over the long sides of said pad and stitched thereto, each of said tapes being approximately five times the length of said pad, said mask being used by tying each end of said tapes around the head of the wearer such that the said non-porous layer is on the side away from the face, said porous pad and cellulose layer absorbing water and contaminants from the air as it passes along said pad and layers, said non-porous sheet serving to cause said passing air to travel further through said porous material, and said mask being disposable after use.

3. A disposable mask comprising, a flexible porous absorbent pad of size to cover the nose and mouth of a human being, said pad being made of loosely piled layers of non-woven absorbent cellulose material, and inside cellulose material layer congruent with and fastened to said pad and reinforced with threads, a non-porous and impervious film on the outside of said mask, positioned so as to cover all except the two end portions of said pad,

and fastened on four sides to said pad, said layers having spaced and parallel longitudinally extending pleats therein, stitching at the end portions of said pad maintaining said pleats, and flexible binding tapes fastened to the edges of said pad, said tapes being of such length as can be tied around a head, said mask being used by tying each of said tapes around the head of the wearer such that said non-porous layer is on the side away from the face, and said porous pad and cellulose layers absorbing water and contaminants from the air as it passes along said pad and layers.

4. A disposable surgical mask comprising, a flexible porous absorbent pad of size to cover the nose and mouth of a human being, said pad being made of from 5 to 15 layers of cellulose absorbent material, said pad being reinforced with threads, longitudinally extending parallel pleats in said pad, stitching adjacent the end portions of said pad maintaining said pleats, a non-porous and impervious material attached to said pad and positioned so as to overlie all except the end portions of said pad, and flexible binding tapes attached to said pad, said tapes being of length such that said tapes can be tied around a head, said mask being used by tying said tapes around a head, such that said non-porous layer is on the side away from the face, said porous pad and cellulose layers absorbing water and contaminants from the air as it passes along said pad and layers, said non-porous sheet serving to cause said passing air to travel further through said porous material, and said mask being disposable after use.

5. A disposable surgical mask comprising, a reinforced absorbent pad made of a number of sheets of cellulose absorbent product, said pad having pleats, securing means on said pad for maintaining said pleats, a non-porous and impervious outside layer attached to said pad smaller in size than said pad and covering the central portion thereof, and two flexible strips of material fastened to said pad and of length such that they can be tied around the head of a human, said mask being used by tying said strips of material around a head, said pad absorbing water and contaminants from the passing air, said non-porous sheet directing said air along said pad, and said mask being disposable after use.
